UNITED STATES PATENT OFFICE.

JAMES A. PHELPS, OF CLEVELAND, OHIO.

DIE-STOCK.

1,036,001.

Specification of Letters Patent. Patented Aug. 20, 1912.

Application filed July 31, 1911. Serial No. 641,635.

REISSUED

To all whom it may concern:

Be it known that I, JAMES A. PHELPS, a citizen of the United States, residing at Cleveland, in the county of Cuyahoga and State of Ohio, have invented certain new and useful Improvements in Die-Stocks, of which the following is a specification.

The invention relates to die stocks for cutting screw threads upon cylindrical bars and pipes.

The objects of this invention are to provide novel means for receding the dies as the thread is cut to form tapered threads; to provide means for retracting the dies from the work after the thread has been cut to permit the ready removal of the die stock from the work; to provide means for changing the dies to cut threads on various sized pipes and bars in connection with the foregoing feature; and to provide an oil reservoir for lubricating the rotating parts and means for preventing the chips from working between the said parts.

With the above and other objects in view this invention is embodied in the construction, arrangement and combination of parts as hereinafter described and claimed and as shown in the accompanying drawings, in which similar reference characters indicate similar parts, and in which,—

Figure 1 is a front view of the die stock. Fig. 2 is a section on the line 2—2 of Fig. 1, parts being shown in moved position for purpose of clearness. Fig. 3 is a view taken in a diagonal position between the top and side as indicated by the arrow 3 in Fig. 1, parts broken away and the relative parts being shown as telescoped.

Referring specifically to the drawings, 5 indicates the tubular work holder or body of the die stock which has several work engaging members 6 mounted in the rear end thereof. These members 6 are arranged to be given an outward and inward thrust by the cam plate 7 to engage or release the work to hold the work and body 5 securely together. This device being old in the art is therefore not described in detail and is just shown as a means for securing the work and body together. Concentric annular recesses 8 and 9 are formed in the front end of the body which form an annular wall 12 or common wall of the recesses. This wall 12 projects beyond the remainder of the

body 5 and has external and internal screw threads on its outer end. This is done for convenience in cutting the threads thereon. A duct 11 passes through the wall 12 to form a communicating passage between the two recesses 8 and 9 which form oil reservoirs. A suitable valve or cap 10 passes through the body 5 from the exterior thereof to the recess 8 to provide an inlet for injecting oil or the like into the recess 8. The oil also enters recess 9 through the duct 11.

14 indicates the die holder, being annular in shape and having the rear tubular extension 20 which has external screw threads thereon, and this die holder has the annular recess 15 in the front end thereof and four die ways 49 cut in the said end in which the dies 19 are radially slidable. An annular groove 16 is arranged in the rear end of the die holder 14 and is concentric with the tubular extension 20, being spaced outwardly therefrom. The forward end of a sleeve 13 fits within the groove 16 and has internal screw threads cut therein. The sleeve 13 is in screw threaded engagement with the external surface of the wall 12, 80 while the tubular extension 20 of the die holder is in engagement with the internal threads of the wall 12. The rear ends of the extension 20 and sleeve 13 fit snugly into the respective recesses 9 and 8. The pitch of the threads of the extension 20 are the same as the pitch of the thread cut by the dies 19 thus as the die holder is turned the same is led inward to properly lead the dies 19 on the work, while the pitch of the threads on the sleeve 13 is slightly less than the pitch of the threads on the said extension whereby the said sleeve moves a little slower longitudinally than the die holder as the die holder is turned, for the purpose hereinafter described.

An annular plate 27 is arranged in front of the die holder 14 and has an annular channel 40 in the rear face thereof adjacent the recess 15 of the die holder. An outer ring 26 and an inner ring 24 fit snugly within the outer and inner side walls, respectively, of the channel 40 and are secured rigidly to the outer end of the die holder 14 by means of screws 35. These rings 24 and 26 receive between them a cam ring or plate 45 having four cams or cam leaves 47 on the rear face thereof. These cams are

not only curved away laterally from the center as has been heretofore used but diverge outwardly toward their rear ends. The dies 19 have correspondingly shaped notches 48 into which the said cams fit.

A plurality of studs 17, preferably four, pass through arcuate slots 50 in the die holder from the groove 16 into the recess 15 and have reduced inner ends 18 which are 5 screw threaded and engaged in the front end of the sleeve 13 to make the studs 17 rigid therewith. Bolts 21 pass through the plate 27 from the front face thereof in alignment with studs 17 and have the reduced 10 inner ends 23 which are screw threaded into the outer ends of the studs 17. The body of the bolts 21 are smaller in diameter than the studs 17 and a washer 22 is arranged on each bolt 21 and seats on the stud 17. These 15 bolts 21 also pass through the arcuate slots 39 in the cam ring 45. Thus the plate 27 and sleeve 13 are made to revolve together but the plate and sleeve having a longitudinal 20 slideable and limited rotary movement with 25 respect to the die holder. The cam ring 45 has a limited rotatable movement with respect to the plate 27 and die holder 14 as allowed by the slots 39 but this cam ring is held snugly against the plate 27 by the 30 washers 22.

The cam ring 45 has a radial slot 25 in its lower end in which projects the eccentric lug 42 of the head 46 which is screw threaded into the plate 27. This head 46 has a handle 35 28 for turning same and as it is turned the eccentric lug 42 working in slot 25 causes the rotation of the cam ring 45 to move the dies 19 radially to or from the center of the device to engage or disengage the work, the 40 cams 47 sliding laterally in the notches 48 of the dies to move the same. This forms convenient means for retracting the dies from the work when the thread has been cut on the work.

45 An eye 41 is arranged on the top of the die holder 14 and a lip 30 is arranged on the upper end of the plate 27 in front of the eye 41 and has an arcuate slot therein. A pin 33 passes through the eye 41 and has 50 the front end thereof butting against the lip 30 and has a reduced extension 29 passing through the arcuate slot in the lip 30, being screw threaded on its outer end. The pin 33 has a longitudinal groove 32 therein 55 in which a key 31 projects from the eye 41 to prevent the pin from revolving and allowing the sliding movement thereof in the eye. A pointer 36 is secured on the extension 29 and is held from movement thereon 60 by a key 34. A nut 37 having the handle 38 is screwed on the end of the extension 29 to clamp the lip 30 tightly between the pointer 36 and the pin 33 thus holding the plate 27 rigid with the die holder 14. Upon 65 loosening the nut 37, the plate 27 can be

70 moved or revolved to carry the cam rings with same to adjust the dies 19 for various sizes of stock, a scale of graduations being arranged on the plate 27 upon which the pointer 36 indicates the size to which the dies have been set. The nut 37 is then tightened and the device is ready for use. This mechanism forms suitable means for changing the size of the threads to be cut.

75 In operation, the body 5 is secured on the work, the work being brought against the dies 19. The die holder 14 is then rotated in the proper direction by handles 44 disposed in sockets 43 provided on the said holder and the dies are carried around the 80 work and are led backward thereon by the lead threads on the tubular extension 20 as described, the plate 27, cam ring 45, sleeve 13 and die holder all being rotated in unison. As the die holder works its way backward, the sleeve 13 moves slower or has a 85 slower rate of longitudinal movement thus causing the plate 27 and cam ring 45 to be gradually forced longitudinally away from the die holder. As the cam ring 45 moves outward, the dies are caused to climb up toward the ends of the cam to recede slowly from the center thus cutting a tapered thread on the work. When the thread has 90 been cut on the work the handle 28 is turned to swing the cam ring 45 and the dies are retracted from the work. The die holder is reversed to bring it to normal position and the body 5 having been removed from the 95 work and handle 28 having been turned back leaves the device ready for a new operation.

100 It will be seen that the sleeve 13 and tubular extension 20 telescope into the recesses 8 and 9 and the threads are lubricated by the oil contained within the said recesses. They 105 are also in this manner protected from chips cut from the work. The objects are in this manner attained in an efficient and novel manner, it being understood that this device is susceptible of alterations in its construction, arrangement and combination within the scope of the appended claims without departing from the spirit of the invention. It is also understood that instead of rotating the die holder and dies the work 110 and work holder may be rotated which is a 115 reversal of operation.

Having described my invention, what I claim as new is:—

1. In a die stock, a work holder, a die 120 holder rotatably mounted thereon to move longitudinally, a die carried by the die holder, and a member rotatable with the die holder and movable at a different rate of longitudinal speed and connected to the die 125 to move same radially.

2. In a die stock, a work holder, a die 130 holder rotatably mounted thereon to move longitudinally, a die carried by the die holder, and a cam plate rotatable with the

die holder and at a different rate of longitudinal speed and having a cam to move the die radially.

3. In a device of the character described, 5 the combination of a work holder, a die holder having a screw threaded engagement therewith, a die carried by the die holder, a member having a screw threaded engagement with the work holder, the pitches of 10 the above mentioned screw threads being varied, and operative means connected to the said member and die to move the die radially upon the die holder being rotated.

4. In a device of the character described, 15 the combination of a work holder having concentric annular recesses in the front end thereof, a die holder and a sleeve having a screw threaded engagement with the wall between the recesses and adapted to telescope into the said recesses, the screw 20 threads of the respective parts being varied in pitch, dies carried by the die holder, and an operative connection between the said sleeve and dies for moving the dies radially 25 upon the die holder and sleeve being rotated.

5. In a device of the character described, the combination of a work holder, a die holder having a screw threaded engagement therewith, a die carried by the die holder, 30 a member having a screw threaded engagement with the work holder, the pitches of the above mentioned screw threads being varied, and a cam plate movable with the said member and having a cam which 35 diverges away from the center of the work holder toward one end thereof, the said cam being engaged to the said die.

6. In a device of the character described, the combination of a work holder, a die 40 holder rotatably mounted thereon, a die carried by the die holder, a plate rotatable with the die holder and having a longitudinal movement therewith, a cam plate carried longitudinally with the said plate and 45 rotatable therewith having a cam thereon which curves laterally away and diverges toward one end from the center of the die holder and which engages the said die, means for moving the said plate longitudinally with respect to the die holder upon 50 the die holder being rotated, and means for rotating the cam plate with respect to the said plate.

7. In a device of the character described, 55 the combination of a work holder, a die holder rotatably mounted thereon, a die

carried by the die holder, a plate rotatable with the die holder and having a longitudinal movement therewith, a cam plate carried longitudinally with the said plate and 60 rotatable therewith having a cam thereon which curves laterally away and diverges toward one end from the center of the die holder and which engages the said die, means for moving the said plate longitudinally with respect to the die holder upon 65 the die holder being rotated, means for rotating the cam plate with respect to the said plate, and means for adjusting the said plate with respect to the die holder to adjust the 70 die therein.

8. A device of the character described comprising a work holder, a die holder having a screw threaded engagement with the work holder, a die carried by the die holder, 75 a sleeve concentric with the die holder and having a screw threaded engagement with the work holder, the screw threads of the die holder and sleeve being varied in pitch, a plate mounted to move with the said sleeve, 80 a cam ring mounted to move with the said plate and having a cam thereon which curves laterally away and diverges toward one end from the center of the die holder and which engages the said die and means 85 for rotating the cam ring with respect to the said plate.

9. A device of the character described comprising a work holder, a die holder having a screw threaded engagement with the 90 work holder, a die carried by the die holder, a sleeve concentric with the die holder and having a screw threaded engagement with the work holder, the screw threads of the die holder and sleeve being varied in pitch, a 95 plate mounted to move with the said sleeve, a cam ring mounted to move with the said plate and having a cam thereon which curves laterally away and diverges toward one end from the center of the die holder and which 100 engages the said die, means for rotating the cam ring with respect to the said plate, and means for adjusting the said plate with respect to the die holder to adjust the die 105 therein.

In testimony whereof I affix my signature in presence of two witnesses.

JAMES A. PHELPS.
